UNITED STATES PATENT OFFICE.

GEORGE C. BEIDLER, OF OKLAHOMA, OKLAHOMA.

PRINTING AND DEVELOPING APPARATUS.

951,045.

Specification of Letters Patent.

Patented Mar. 1, 1910.

Application filed March 23, 1907. Serial No. 364,014.

To all whom it may concern.

Be it known that I, GEORGE C. BEIDLER, a citizen of the United States of America, residing at Oklahoma city, in the county of Oklahoma and State of Oklahoma, have invented certain new and useful Improvements in Printing and Developing Apparatus, of which the following is a specification.

- 10 This invention relates to photographic and developing apparatus and particularly to a conveyer for such apparatus for carrying film through the several tanks for developing, fixing and washing the said film.
- 15 An object of this invention is to provide novel means for causing two conveyers, which act in conjunction, for carrying the film to run on the same roller or set of rollers and maintaining the same relative movement.
- 20 It is a well known fact that if the two belts run on the same roller, one in contact with the other, that the upper belt will travel farther than the lower belt and thus the travel of the two belts is not uniform.
- 25 I overcome the objections above indicated through the novel means for causing a part or an attachment of the outer belt to contact with the roller so that the movement of the roller is communicated to both belts simultaneously by reason of the contact of the belts with the roller.

This device is intended to be used in conjunction with an apparatus similar to that disclosed in my Patent No. 810,388, dated January 23, 1906, and for the purpose of an understanding of the full use of the invention reference is made to said patent.

40 In describing the invention in detail, reference will be had to the accompanying drawings forming a part of this application wherein like characters denote corresponding parts in both views, in which—

45 Figure 1, is a view in elevation, partly in section, showing the side of the apparatus with the invention applied thereto. Fig. 2, is a transverse sectional view showing one of the rollers in elevation with the belts in section.

50 In these drawings A, denotes an apparatus having a series of rollers over which belts are run, the inner belt B, contacting with the rollers throughout its width while the belt C, termed the outer belt, is designed

to travel in conjunction with the inner belt and take motion from the said rollers. In order to effect the foregoing, it is my purpose to have the outer belt overlie the inner belt and have side extensions projecting beyond the edges of the inner belt, it being understood that the said inner belt must not extend the full width of the rollers. The projecting edges of the outer belt are provided with bindings D, which are secured to the inner face of the outer belt by stitching or cement, or by any other approved means and it is my purpose to have the binding of slightly greater thickness than the inner belt in order to provide a small space between the inner and outer belt for the purpose of receiving the film or prints which may be run between the said belts.

Fig. 2 illustrates fully the relation of the inner and outer belts, and the relation of the binding strips to the inner belt. As the rollers are driven, both belts are positively driven in unison but independently, or in other words, both belts take motion from the same source of power, *i. e.* the rollers, hence there will be no creeping of the belts or wrinkling of paper carried between them. When these belts are utilized in conveying paper film through liquid baths, the paper becomes soft and pulp-like and it is necessary to a successful operation of the device that there shall be no movement of one belt relative to the other which would cause these films to be drawn over the surface of the belts. To make an effective device, the film must lie on the belt or conveyer and be carried by it without moving on the conveyer except when it is removed.

A detail description of the apparatus is believed to be unnecessary as the sole purpose of this application is to deal with the belts and the relation of the belts to the rollers.

What I claim as my invention is:—

1. In a printing and developing apparatus, an inner and outer belt adapted to travel in unison, rotary members over which the belts are run, and means on the outer belt adapted to contact with the rotary members for causing the belts to travel at the same rate of speed.

2. In a printing and developing apparatus, suitable rotating members, belts thereon, one belt overlying the other belt, binders on

one belt contacting with the rotating members, the said belt and its binders embracing the under belt.

3. In a printing and developing apparatus, the combination with rollers for driving belts, a belt adapted to contact with the rollers throughout its width, a belt overlying the first mentioned belt and extending beyond the edges of the said first mentioned belt, and binders on the second mentioned

belt on each side of the first mentioned belt adapted to contact with the rollers engaged by the first mentioned belt.

In testimony whereof I affix my signature in the presence of two witnesses, this 15th day of March, 1907.

GEORGE C. BEIDLER.
